US00D708635S

(12) **United States Design Patent**
Capela et al.

(10) **Patent No.:** US D708,635 S
(45) **Date of Patent:** ** Jul. 8, 2014

(54) **DISPLAY SCREEN OR PORTION THEREOF
WITH ICON**

(71) Applicant: **Apple Inc.**, Cupertino, CA (US)

(72) Inventors: **Jay Christopher Capela**, Santa Cruz, CA (US); **Alexander Charles MacLean**, San Jose, CA (US); **Parthibhan Mohanraj**, Cupertino, CA (US); **Roger Rock Rosner**, Mountain View, CA (US)

(73) Assignee: **Apple Inc.**, Cupertino, CA (US)

(**) Term: **14 Years**

(21) Appl. No.: **29/435,272**

(22) Filed: **Oct. 22, 2012**

(51) **LOC (10) Cl.** 14-04

(52) **U.S. Cl.** **D14/489**
USPC **D14/489**

(57) **CLAIM**

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing our new design; and,

FIG. 2 is a front view of a second embodiment thereof.

The broken lines around the Figures showing a display screen or portion thereof form no part of the claimed design.

**1 Claim, 1 Drawing Sheet
(1 of 1 Drawing Sheet(s) Filed in Color)**
